TEMPERATURE RETAINING COVER FOR BABY
BOTTLES AND OTHER RECEPTACLES

Filed Jan. 24, 1948

INVENTOR.

WILLIAM KRAMER

BY

John H. Blackley
ATTORNEY

to completely or substantially completely cover the bottom of the bottle. It is formed by binding the bottom edges of the layers 14', 15' and 16' loosely with a strip of tape 22, leaving a channel 23 for the draw string 13'.

If desired, the discs 19, which are of negligible insulating value, may be made of waterproof fabric so that they will not absorb milk and saliva during nursing.

It is to be understood that this heat insulating protective covering may be used on receptacles of all shapes and sizes.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new, and desire to secure by United States Letters Patent is:

A hood for use with a baby bottle having a nipple, comprising an insulated tubular casing having open top and bottom ends for enclosing the bottle from a point slightly below the top thereof to the bottom thereof, a draw string at the open bottom of said tubular casing for closing the open bottom of said tubular casing

about the bottom of the bottle, superimposed discs of waterproof material formed with concentric aligned openings extended across the top of the bottle with the nipple extending through said aligned openings, said discs having their peripheral edges bent downward along the sides of the top portion of the bottle and stitched to the material of said tubular casing about the open top end thereof, said discs having the edge portions thereof surrounding the concentric openings bent inward and outward between the adjacent faces of said discs, and a line of stitches passed through said discs and said edge portions securing said edge portions in position between the adjacent faces of said discs.

WILLIAM KRAMER.
